UNITED STATES PATENT OFFICE.

WILLIAM KELLY, OF DETROIT, MICHIGAN, ASSIGNOR TO MAXWELL MOTOR COMPANY,
INCORPORATED, OF DETROIT, MICHIGAN.

STARTER FOR GAS-ENGINES.

1,120,205.

Specification of Letters Patent.

Patented Dec. 8, 1914.

Application filed September 9, 1911. Serial No. 648,466.

To all whom it may concern:

Be it known that I, WILLIAM KELLY, citizen of the United States, residing at Detroit, county of Wayne, State of Michigan, have 5 invented a certain new and useful Improvement in Starters for Gas-Engines, and declare the following to be a full, clear, and exact description of the same, such as will enable others skilled in the art to which it 10 pertains to make and use the same, reference being had to the accompanying drawings, which form a part of this specification.

My invention relates to starters for gas engines and an object of my improvements is 15 to provide an improved apparatus by which a supply of compressed air may be controlled and governed to start a gas engine.

I have shown the apparatus embodying my improvements in the accompanying 20 drawings in connection with a four-cylinder automobile engine.

In the drawings:—Figure 1, is a plan view of the apparatus embodying my invention, and so much of an automobile as is convenient 25 to illustrate the connection of said apparatus therewith. Fig. 2, is an enlarged sectional detail view of the portion of the apparatus attached to the dash-board of the vehicle. Fig. 3, is a perspective view of the 30 distributing disk. Fig. 4, is a plan view of the casting and attached parts in which the distributing and governing apparatus is chiefly contained. Fig. 5, is an elevation of the apparatus shown in Fig. 4, looking toward the side that is toward the bottom of 35 the sheet in Fig. 4. Fig. 6, is a view partly in section on the line 6—6 Figs. 4 and 7, the upper part of the casing being shown in section and the lower in elevation with the distributing disk and its casing removed. Fig. 40 Fig. 7, is a section on the line 7—7 Fig. 5. Fig. 8, is a view similar to Fig. 6 except that the distributing disk is shown in position. Fig. 45 Fig. 9, is a perspective view of a multiple piston valve.

A is a reservoir containing compressed air and B is a pipe leading therefrom to valves upon the dash-board A¹.

The construction of the valves on the 50 dash-board is illustrated in detail in Fig. 2. C is a needle valve by which the passage B may be permanently closed to prevent leakage. D is a passage communicating with the passage B when the needle valve C is open and at the other end communicating

with a chamber d. b is a pipe leading from the chamber d to a convenient point where it will be provided with a stop cock of any ordinary construction, not shown, by which the air may be drawn from the reservoir A. 60 At an end of the chamber d is a valve E upon the inner end of a spindle f. The outer end of the spindle f is provided with a pedal F. e is a spring adapted to normally hold the valve E closed. G is a pipe communicating 65 with the chamber d when the valve E is open and leading to the casting a a in which the main distributing apparatus is located.

The casting a a constitutes the casing of the apparatus constituting the distributor. 70 J, J¹, J², J³ are the cylinders of a gas engine. j j¹ j² j³ are passages in the casting a a communicating respectively with the cylinders J J¹ J² J³, as shown in Fig. 1. In the upper part of the casting a a is formed a horizontal cylindrical chamber L L and with this chamber the passages j j¹ j² j³ communicate at intervals as shown in Figs. 6 and 8. E^x indicates an exhaust passage formed in the casting a a. This is shown as extending laterally for convenience. In the cylindrical chamber L L there is located a piston valve N N having an enlarged piston-like head M. m is a spring acting on the head M of the piston valve N N to move it to the left hand end of its travel, as shown in Figs. 6 and 8. n n indicate grooves in the piston valve N N. When the piston valve N N is at its extreme left position it closes all of the passages j j¹ j² j³ and E^x. When said valve is moved toward the right as shown in said figures the grooves n register with said passages and put them respectively into connection with the apertures j^a j^{1a} j^{2a} j^{3a} and E^{xa}, in a circular faced-off surface P. There is a concentric opening p in the faced-off surface P. Now referring more particularly to Fig. 3 but also to Figs. 7 and 8: Q is a circular disk hollowed out to form a circular cavity Q² concentric with the said disk leaving a 100 smooth face between the cavity Q² and the periphery of the disk. Q¹ is a trunnion extending from the bottom of the cavity Q² of the disk Q concentric therewith formed to engage as a part of an Oldham coupling. The casting a a is secured to the engine so that the cam shaft K (Fig. 4) with its end suitably formed shall engage the trunnion Q¹ so as to rotate the disk Q. Q⁴ is a cavity 105 extending toward the periphery of the disk

Q from the cavity Q². The disk Q is cut away at Q³ part way in toward the cavity Q². I, is a cover, or casing, closing tight over the disk Q which is placed with its 5 trunnion Q¹ in the hole p, and the bearing surface between its periphery and the opening Q² fitting closely upon the faced-off portion P of the casting a a.

The arrangement of the apertures j^a j^{1a} j^{2a} 10 is such that they shall be covered by the bearing surface of the disk Q except when the cut away portion Q³ registers with one of said apertures or the cavity Q⁴ registers with one of said apertures. The exhaust 15 aperture E^{xa} opens through the faced-off surface P at such a point that it is always in communication with the cavity Q².

S (Fig. 7) is a ball adapted to fit and reciprocate in a cavity in the cover of casing 20 I and to bear against the center of the disk Q.

s is a spring acting to press the ball S inward and thereby press the disk Q firmly against its seat.

25 H is a pipe, or passage, connected with the pipe G and also opening into the casing I outside of the disk Q as indicated at H¹ in Fig. 7.

h is a pipe or passage leading from the 30 passage H to the enlarged end of the cylindrical passage L L so that any compressed air passing through the pipe h shall enter the chamber L L and act against the enlarged end M of the piston valve N to press 35 the same to the position which shall open the passages j j¹ j² j³ to their respective apertures j^a j^{1a} j^{2a} j^{3a} and also the exhaust passage E^x with its aperture E^{xa}.

The operation of the above described device is as follows:—Wishing to start the engine the needle valve C being open the operator presses upon the pedal F with his foot opening the valve E (Fig. 2) and permitting the compressed air from the reservoir A to pass through from the pipe B to the passage D and chamber d to the pipe G, to the passage H and from there to the casing I outside of the disk Q, and also through the pipe h to the cylindrical chamber L L, its pressure actuating the piston valve N N to a position to open all of the passages j j¹ j² j³ and E^x. At this time the cut away portion Q³ of the disk Q will be registering with one or the other of said apertures, as for instance j^a (Fig. 8) and the hollowed out portion or cavity Q⁴ of said disk would be registering with the next one of said apertures, as for instance j^{3a}. In this case the compressed air from the reservoir will 50 pass through the aperture j^a and through j to the cylinder J above the piston therein, while the upper end of the piston in the cylinder J^a which will be then compressing, will be open through the passage j³, and aperture j^{3a} to the hollows or cavities Q².

and Q⁴ and thence to the exhaust aperture E^{xa}, so that the pressure will be relieved from the compressing cylinder, the other cylinders would have either the exhaust or inlet valve open and would not resist the 70 turning effect of the compressed air.

The casting a a is provided with slots o o formed in the arcs of a circle concentric with the disk Q.

O O are lag bolts engaging in the slots o o to fix the casting in its desired position.

To get proper relative positions of the disk and the aperture in the faced-off surface thereon the casting a a may be turned about its center as indicated by dotted lines 20 in Fig. 5 and fixed in their required position.

What I claim is:—

1. In an apparatus of the kind described, the combination of a source of compressed air, a multiple cylinder gas engine, a distributor, a passage leading from each of the cylinders of said gas engine to said distributor, a valve adapted to open and close all of said passages, a valve adapted to be actuated by the operator between said source of compressed air and said distributor, and means whereby the pressure of the compressed air actuates the first named valve to open all of the passages between said distributor and the cylinders of the engine when the valve between the reservoir and distributor is open.

2. The combination of a source of compressed air, a multiple cylinder gas engine, a distributor located between said source of compressed air and said engine, a pipe leading from said source of compressed air to said distributor and a passage leading from said distributor to each of the cylinders of said engine, means in said distributor for connecting each of said passages leading to the cylinders of the engine successively to the pipe leading to the source of compressed air, and means in said distributor for placing the passages leading from said distributor to the cylinders of said engine successively into communication with the atmosphere arranged so that the cylinder which is on its compression stroke shall be placed in communication with the atmosphere.

3. The combination of a source of compressed air, a multiple cylinder gas engine, a distributor located between said source of compressed air and said engine provided with an exhaust passage, a pipe leading from said source of compressed air to said distributor and a passage leading from said distributor to each of the cylinders of said engine, means in said distributor for connecting each of said passages leading to the cylinders of the engine, successively to the pipe leading to the source of compressed air, and means in said distributor for placing the passages leading from said distributor to

the cylinders of said engine successively into communication with the said exhaust passage arranged so that the cylinder which is on its compression stroke shall be placed in communication with said exhaust passage, a valve adapted to be actuated by the operator located between said source of compressed air and said distributer, a second valve normally acting to close the exhaust passage from said distributer, and means whereby the last named valve is opened when the valve between the source of compressed air and the distributer is actuated to permit compressed air to flow to said distributer.

4. The combination of a source of compressed air, a multiple cylinder gas engine, a distributer for the compressed air, located between said source of compressed air and said gas engine, a passage leading from said source of compressed air to said distributer, a passage leading from each of the cylinders of said engine to said distributer, said distributer being provided with a faced-off surface having apertures therein connecting with each of the passages to the cylinders, said distributer having an exhaust passage, a rotary disk upon said faced-off surface adapted to cover the apertures therein, said disk being provided with a peripheral aperture adapted to register successively with the apertures in said faced-off surface, to uncover the same, said disk being provided with a central cavity, the said exhaust passage communicating with said cavity, said disk being also provided with a cavity extending outward from the first named cavity and adapted to register successively with each of said apertures, and a casing inclosing said disk, the passage from said source of compressed air communicating with said casing.

5. The combination of a source of compressed air, a multiple cylinder gas engine, a distributer for the compressed air located between said source of compressed air and said gas engine, a passage leading from said source of compressed air to said distributer, a passage leading from each of the cylinders of said engine to said distributer, said distributer being provided with a faced-off surface having apertures therein connecting with each of the passages to the cylinders, said distributer having an exhaust passage, a rotary disk upon said faced-off surface adapted to cover the apertures therein, said disk being provided with a peripheral aperture adapted to register successively with the apertures in said faced-off surface to uncover the same, said disk being provided with a central cavity, the said exhaust passage communicating with said cavity, said disk being also provided with a cavity extending outward from the first named cavity, and adapted to register successively with each of said apertures, a casing in-

closing said disk, the passage from said source of compressed air communicating with said casing, a piston valve adapted to normally close the passages from said distributer to the cylinders of the engine, means for actuating said piston by compressed air to open the same having its supply passage communicating with the passage conveying compressed air to said distributer.

6. The combination of a source of compressed air, a multiple cylinder gas engine, a distributer for the compressed air located between said source of compressed air and said gas engine, a passage leading from said source of compressed air to said distributer, a passage leading from each of the cylinders of said engine to said distributer, said distributer being provided with a faced-off surface having apertures therein connecting with each of the passages to the cylinders, said distributer having an exhaust passage, a rotary disk upon said faced-off surface adapted to cover the apertures therein, said disk being provided with a peripheral aperture adapted to register successively with the apertures in said faced-off surface, to uncover the same, said disk being provided with a central cavity, the said exhaust passage communicating with said cavity, said disk being also provided with a cavity extending outward from the first named cavity and adapted to register successively with each of said apertures, a casing inclosing said disk, the passage from said source of compressed air communicating with said casing, said disk being adapted to be connected with the cam shaft of the engine.

7. The combination of a source of compressed air, a multiple cylinder gas engine, a distributer for the compressed air located between said source of compressed air and said gas engine, a passage leading from said source of compressed air, to said distributer, a passage leading from each of the cylinders of said engine to said distributer, said distributer being provided with a faced-off surface having apertures therein connecting with each of the passages to the cylinders, said distributer having an exhaust passage, a rotary disk upon said faced-off surface adapted to cover the apertures therein, said disk being provided with a peripheral aperture adapted to register successively with the apertures in said faced-off surface, to uncover the same, said disk being provided with a central cavity, the said exhaust passage communicating with said cavity, said disk being also provided with a cavity extending outward from the first named cavity and adapted to register successively with each of said apertures, a casing inclosing said disk, the passage from said source of compressed air communicating with said casing, said distributer being pro-

vided with a casing, and means for adjusting said casing to different angular positions about the axis of said disk.

8. In an apparatus of the kind described, 5 the combination of a casing, a multiple-cylinder gas engine, a passage leading from said casing to each of the cylinders of said engine, a source of compressed air, a passage leading from said source to said casing, a valve in said casing, means for operating said valve from said engine, said valve being adapted to put a cylinder having its piston on the working stroke into communication with the source of compressed air 10 and a cylinder on its compression stroke into communication with the atmosphere.

9. The combination with a multi-cylinder explosive engine, of a source of compressed fluid, a valve member communicating with 20 said fluid source, communication between the fluid source and the respective cylinders, means for moving the valve to successively bring the cylinders into communication with the source of compressed fluid, and means

for successively venting the cylinders while 25 on their compression stroke and simultaneously with the admission of the compressed fluid to the companion cylinder.

10. In a starting device for explosive engines, the combination with a multiple cylinder engine and a tank containing compressed fluid, of a passage between the cylinders and the tank, a valve for controlling said passage, venting passages between the cylinders and the said valve, said valve having ports for venting certain cylinders while the companion cylinder is being supplied with compressed fluid, and means for preventing communication between the tank and the cylinders during the normal operation of the machine. 30 35 40

In testimony whereof, I sign this specification in the presence of two witnesses.

WILLIAM KELLY.
